UNITED STATES PATENT OFFICE

JULIUS LARSEN, OF COPENHAGEN, DENMARK, ASSIGNOR TO EUGEN E. WIRTHS, OF BROOKLYN, NEW YORK.

MECHANISM FOR OPERATING CIRCULAR NEEDLES.

No. 910,829.

Specification of Letters Patent.

Patented Jan. 26, 1909.

Application filed January 26, 1907. Serial No. 354,201.

To all whom it may concern:

Be it known that I, JULIUS LARSEN, citizen of the Kingdom of Denmark, and a resident of Copenhagen, Denmark, Silkegade 13, have 5 invented new and useful Improvements in Mechanism for Operating Circular Needles, of which the following is a specification.

It is well known that curved needles are sometimes used in sewing-machines especially 10 for sewing foot-wear, these needles performing an up and down movement through holes previously made by an awl. These needles, however, are all hook-needles, which by means of the hook draw the upper thread up 15 through the hole made by the awl. But curved needles provided with an eye that made the holes in the leather themselves, so that continuous sewing might be performed, have not been known formerly. 20 My invention relates to a sewing-machine using a curved needle to which is imparted a movement so that it becomes possible to force the needle through the sole leather without boring holes previously, thereby making it 25 possible to attach the soles without any preliminary work or treatment whatever.

Figure 1 is a fragmentary side elevation of a sewing machine provided with my improved needle and with a presser member for 30 actuating the same, the parts being in such position that the needle occupies its uppermost position; Fig. 2 is a side elevation of the mechanism shown in Fig. 1; Fig. 3 is a 35 side view, partly in section and partly in elevation, showing a part of the means for supplying power to the needle.

1 is a fixed plate on which the needle-press arm 2 can slide up and down. This arm always presses slidably against the fixed plate 40 1 and has a positive up and down motion. The lower part of this arm is forked and the prongs are provided with a slanting and curved slot 3 the upper part of which is horizontal. This fork incloses the needle-holder 45 4 formed like a single armed lever, and is turnable on the bolt 5 and provided with a pair of guide-rollers 7. In the extreme end of the needle-holder 4 is fixed the needle 6. In the plate is made a groove 8 for giving necessary room for the guide-rollers 7. At first 50 the needle moves slowly at the downward movement of the needle-press arm 2, during

which the rollers 7 move in the slot 3, but at the moment the point of the needle 6 has reached the leather, the roller 7 has reached into 55 the horizontal part of the slot about underneath the center of the needle-press arm and the speed of the needle's motion is thereby increased and, owing to the direct transmission of power, the motion becomes so powerful that the needle can pass through sole-leather 12-14 mm. in thickness. The return of the needle is performed in a similar manner, the passage through the leather being quick while the latter part of the movement 60 takes place at a lower speed. By thus causing a portion of each movement of the needle to take place at a higher speed, a safer perforation is obtained and the hole in the leather closes instantly, which would not be the case, if the 65 needle was allowed to remain in the leather more than a fraction of a second.

The arm 2 carries a plate 9 provided with a slot, and adjacent to this plate is a wheel 10 mounted upon a revoluble shaft 11. A boss 75 12 carried by the wheel 10 projects into the slot of the plate 9, so that rotation of the shaft 11 causes the plate 9, and consequently the arm 2, to reciprocate vertically.

What I claim, and desire to secure by Letters Patent is:

1. In a device of the character described, the combination of a needle, a needle holder for supporting the same, said needle holder being mounted upon a pivot and free to 85 swing, and being further provided with a roller and a presser member provided with a curved slot receiving said roller for the purpose of moving said needle holder at a progressively increasing rate of speed, as said 90 needle is driven through the work.

2. The combination of a needle holder, rollers mounted thereupon, a presser member provided with slots through which said rollers extend, the general direction of said 95 slots being arcuate, thus serving as cams for moving said needle holder at a progressive rate of speed.

Signed by me at Copenhagen, Denmark, this 15th day of December 1906.

JULIUS LARSEN,

Witnesses:

CHARLES HUDE,
A. CHRISTENSEN.
